CELL-DOOR OPERATING AND LOCKING MEANS.

No. 897,317.

Specification of Letters Patent.

Patented Sept. 1, 1908.

Application filed July 17, 1907. Serial No. 384,261.

To all whom it may concern:

Be it known that we, RICHARD C. STEWART and WALLACE A. STEWART, citizens of the United States, and residing at Covington, 5 Kenton county, State of Kentucky, have invented certain new and useful Improvements in Cell-Door Operating and Locking Means; and we do declare the following to be a clear, full, and exact description of the invention, 10 attention being called to the accompanying two sheets of drawings, with the reference characters marked thereon, which form also a part of this specification.

In penal institutions and places of detention like jails and penitentiaries, means have been provided to manipulate and to control the doors of a series of cells from one certain position and by means provided thereat so as to dispense with direct and immediate 20 manipulation of the doors at each cell. The cells in such cases are usually grouped in rows or tiers and generally provided with an inclosed passage or exercising corridor which is arranged in front of them and with which 25 all cells in a particular group communicate by means of their door-openings. The position above referred to and from which such a group of doors is controlled and manipulated, together with the means used for such purpose is usually one outside of this corridor, or 30 in a guard-room, so that the attendant need not necessarily come in contact with any of the prisoners, since he need not pass in front of each cell-door for the purpose of manipulating the same. Doors arranged for such manipulation are usually sliding doors and our present invention relates to doors of that kind and likewise to such which lock also automatically when moving into closing position. 35 Various means and devices have been used for manipulating such doors from the controlling position. They generally comprise instrumentalities for unlocking the doors which, after having been operated, permit the door to be pushed open by the particular cell inmate. This is shown in one of our patents No. 680,288. Means have also been devised whereby a number of doors or any particular one only may be unlocked 40 and thereafter opened as for instance in another one of our patents No. 645,575. Means have also been used whereby an open door may be moved into closing position, in which position it also becomes locked automatically 45 as for instance shown in our patent first men-

tioned (No. 680,288). Means are usually provided whereby an automatically locked door may also in addition be positively or dead locked.

Our present invention provides certain 60 means whereby any one door may be unlocked or a number of them simultaneously.

It provides also means whereby any particular door, or a number of them, after unlocked, may be slid open, and the open doors 65 thereafter again moved into closing position, all manipulations required for the purpose being performed at one point, viz. the position above referred to. The doors become automatically locked as soon as they arrive 70 in closing position. In this position they may also in addition be locked positively, or dead-locked. All these means are also so arranged that for purposes of this general operation which controls all the doors from 75 the outside, they may be rendered inoperative, after which each door may be manipulated directly, and independently locked or unlocked by direct manual operation.

Finally there are also features of construction in general and in detail.

In the following specification and particularly pointed out in the claims at the end thereof, will be found a full description of our invention, together with its operation, parts 85 and construction which latter is also illustrated in the accompanying two sheets of drawings, in which:

Figure 1, shows in elevation with parts broken away, part of the front of a group of 90 cells, two adjoining cells being shown, the door of the first cell being closed and locked by means operating automatically, the door of the second cell being open. Fig. 2, is a ground-plan or horizontal section of the 95 front part of these cells. Fig. 3, is a vertical section of the cell-front. Fig. 4, in a view similar to Fig. 1, shows the upper part of the cell-front shown in said figure the door of the first cell is shown in the act of being opened, 100 the other door being closed and locked by means operating automatically. Fig. 5, is another view similar to Figs. 1 and 4, being limited however to the upper part of the front of the first cell only, the door being shown closed and locked by the automatically operating means as illustrated in the preceding figure, said means however being now positively held in such locking position 105 or dead-locked by additional means. Fig. 110

6, shows the box which contains the manipulating parts of the outfit and is provided at the end of the group of cells. The interior of the box is shown as it appears when viewed 5 from the left side of Figs. 1 and 4, and with its door open. Fig. 7, is a top-view partly in section of the operating and manipulating parts whereby the doors are opened and closed. Fig. 8, is a similar view of the means 10 and parts whereby the door is suspended and whereby it is locked and unlocked, these parts being located below the parts shown in Fig. 7, as may be seen in Fig. 5, above these two views. Fig. 9, is an enlarged vertical 15 cross-section on line 9 of Fig. 5. Fig. 10, is a similar view taken on line 10, of Fig. 5. Fig. 11, is another similar section taken on line 11, of Fig. 5. Fig. 12, is an enlarged sectional detail view of a certain coupling. Fig. 13, is 20 an enlarged sectional detail view of the locking means at the front edges of the doors, and Fig. 14, shows in a similar view holding means at the rear edges of the doors. All of these details will be more fully described 25 hereinafter.

In the drawing, A, B, and C, indicate the first three of a row of cells grouped together for common manipulation from one general position which is indicated at D, and where 30 the means used for such manipulation, locking, unlocking, opening and closing, are located. These means may be inclosed in a box, in which case letter D, may indicate such box. It is provided with a door d, 35 which may be locked so that access to these operating means may be properly controlled.

The cell-fronts which contain the door-openings E, are all open towards a common passage or corridor F, which however may be 40 separated from the position of the attendant at D, by a grated partition f, which is provided with an independently controllable door (not shown). The attendant may therefore manipulate and control all doors 45 from position D, as will be presently described, without coming in contact with any of the prisoners released into passage F, and from whom he is separated by partition f.

The cells are separated from each other by 50 partitions G, and the front wall of each cell between these partitions is shown as consisting of two wall portions H, and J, with the door-openings E, between them. Above the door-openings and between them and 55 the ceiling K, the entire front is closed by a narrow wall-portion l. In front of this narrow portion an elongated, box-shaped inclosure or casing L, is formed, which extends along all of the cell fronts above their door- 60 openings and contains the larger part of the door-manipulating, locking, and unlocking devices.

M, are the doors consisting preferably of open grate-work and provided at their upper 65 edges with hangers N, which have rollers n,

whereby the doors are hung upon track-rails O, (see Figs. 5, and 10,) which are attached to the cell-front above the door-openings and whereby they are supported so as to have a sliding motion. When opened, these doors 70 slide in front of the wall portion J, of the cell front-wall, as shown for cell B, in Figs. 1 and 2. For so manipulating these doors, that is for moving them laterally in either direction from closed to open position and back again, 75 there is a door-manipulating bar P, supported in bracket bearings p, attached to the cell-front. For sake of brevity we call this bar hereafter "door-bar". It has a movement in a longitudinal direction of an extent 80 sufficient to move a door from one of its extreme positions to the other one, see the two doors in Fig. 1. Its operative connection to the doors for such purpose is by means of arms Q, one for each door and which, when 85 in operative position, occupy the space between two lugs q—q, a set of which is carried by each door. For convenience sake they are mounted on one of the two door-hangers N. 90

The longitudinal movement of bar P, is obtained by a screw-movement, which is as follows: At one end of bar P, the left one in this case, is formed or attached a screw or worm R, which is fitted to and occupies a 95 nut r, supported so as to be held fixedly in longitudinal direction but free to rotate, so that when rotated, it will push screw R, with door-bar P, in longitudinal direction. Screw R, is prevented from rotating with the nut 100 by means of a forked guide S, provided with a hub whereby it is rigidly mounted upon the screw said guide being fitted to a guide bar s, attached to the cell-wall so that while it is free to move on bar s longitudinally with the screw, it cannot rotate. (See Figs. 7 and 10). Nut r, is secured to the end of a sleeve T, to which it is rigidly connected, the sleeve being supported in bracket-bearings t, t, 105 within casing L, there being also an additional bracket t', outside in box D, to support the end of the sleeve which projects into this box. The sleeve is rotated by a chain-wheel U, which is provided upon it, which by means of a chain u, is driven from another chain-wheel V, mounted upon a shaft v, which is supported upon a standard W, in the lower part of box D. A crank-handle w, is provided on this shaft for its rotation, access to which however is controlled by 110 door d. X, is merely a guide-roller for this chain. It will now be seen how by operation of crank-handle w, immovable nut r, and the longitudinally movable bar P, the doors may be manipulated for opening and closing, the screw at the end of bar P, moving in and out of sleeve T and back and forth in nut r. 115

The doors lock automatically when moving into closing position, for which purpose they are provided at their front edges with 120

laterally projecting catches 15, the upper edges of which are notched and inclined in front of these notches. When the doors move into closing position, their front edge butts against a hollow jamb 16, the side of which towards the edge of the door is provided with slots 17, to permit catches 15, to enter. Within each jamb and close to the slotted side thereof there is a latch-bar 18, 5 so supported as to have a limited sliding movement on the slotted side of the jamb in a vertical direction, and parallel to this side, it being held to this movement by suitable guiding means, like for instance, headed-pins 19, which project from the inside of the jamb, and pass through slots in the latch-bar. There are also slots 21, in these bars corresponding in size to slots 17, and the longitudinal sides of all slots alike with each 10 other in both sets.

In the normal position of latch-bars 18, and when they are not engaged, the upper ends of slots 21 therein are somewhat below the upper ends of slots 17 in the jambs, the 15 difference in position between the two being substantially equal to the depth of the notches in catches 15. Otherwise, slots 17, and 21, register however, with each other, so that catches 15, may simultaneously enter 20 the slots in the jambs and in the latch-bars when the doors are moving into their closing position as shown in Fig. 13. In due time and during the last part of the closing movement, the inclined edges of catches 15, encounter the upper edge of slots 21 in the 25 latch-bars, which edges thereupon ride up on these inclined edges, whereby said bars are momentarily lifted, to be dropped however immediately into the notches of the 30 catches as soon as these notches have arrived below the upper ends of slots 21, of the latch-bars. These latter are supported to slide and drop freely, so that they act instantly and impelled by their weight, lock 35 the doors at once.

The means used for unlocking the doors are arranged as follows: The latch-bars for their support are each hingedly connected at their upper ends to one end of lifting levers 40 50 55 60 65 70 75 80 85 90 95 100 105 110 115 120 125 130 P, 22, pivotally supported in casing L, one for the latch-bar for each door. By preference and to obtain greater structural rigidity we combine the pivotal supports for these lifting levers with bracket-bearings *p*, of door-bar *P*, and with one of the bracket-bearings *t*, of sleeve *T*, lugs being provided on the underside of these parts which form these supports. The caps of the bearings *p* and *t* are held by bolts at their front flange only, a pin 20 being used at the rear flange, see Fig. 9. Work during erection, in a position not ready accessible is thereby facilitated.

The lifting-levers are shaped as shown in the drawings, with both of their ends depending somewhat below the point of their piv-

otal support. For lifting the connected end of these levers, meaning those ends which connect to the latch-bars, we provide a number of cams 23, projecting from hubs, whereby they are rigidly mounted upon a bar 24, 70 by which they are manipulated for the purpose of unlocking and dead-locking the doors, and which bar 24, we hereafter term locking-bar. This bar is supported below bar *P*, in bearings 25 and is capable of a limited longitudinal movement sufficient to shift cams 23 carried by it in either direction, and so as to act upon either one of the ends of these lifting-levers. For such purpose this locking-bar 24, which extends over the entire length 80 of the connected cell-group is also extended from casing *L*, out into box *D*, where its end is attached to an operating lever 26, pivotally mounted at 27, in box *D*. Referring now to Fig. 1, it will be seen that the first 85 cell-door is closed and locked, and its corresponding cam 23, is in an inactive or neutral position below the particular lifting lever and between the two ends of the same. If now this cam, by means of bar 24, and by 90 manipulation of lever 26, is moved to the right as shown for the first door in Fig. 4, and so as to pass under the connected end of the lifting-lever thereat, this particular end will be elevated and lift latch-bar 18, in jamb 16, 95 out of catches 15, on the door, thereby releasing this latter. The door may now be opened by manipulating door-bar *P*, by means of crank *w*, as shown in same figure which also shows this door in the act of being 100 slid open.

As stated in the preamble the arrangement is such that any particular door, may be unlocked and opened at a time, or a number of them may be unlocked and opened simultaneously. For such purpose cams 23, are arranged on the hubs, from which they project, as follows: There are two cams on each hub, and a set of two such cams for every door, the position of one of which cams in each set 110 with respect to locking-bar 24, and to the lifting-levers, is the same on all hubs and for all doors. This means that if this particular cam on one hub is under its corresponding lifting-lever, all the other cams are in the 115 same position with reference to their lifting-levers, so that if bar 24, is now moved longitudinally to the right, by means of manipulating lever 26, all lifting levers will be acted upon and all latch-bars will be raised so as to unlock all doors. The position of the other of the two cams on each hub is one individual thereto and to the particular door so that, when one of these cams on a particular hub is in position for action under its lifting-lever, 120 none of the other cams on the other hubs are in such a position. This distribution is accomplished by dividing the cams as to position radially around on the hubs, that is to say each cam projects from its hub, or what 125 130

is the same, from bar 24, in a radius located differently from the radius in which any of the other cams project, there being as many different radial positions as there are doors, 5 in addition to the general position of the cam first mentioned for simultaneous operation and which is the same on all hubs. In order to bring now any particular one of the individual cams in position ready for action under its corresponding lifting lever, bar 24, on 10 which the hubs, carrying these cams, are mounted is also given a rotary motion in its bearings 25, in addition to the sliding one it has therein, so that by proper rotation, any 15 particular cam may be placed in position ready for action under its lifting lever. In view of this compound motion, lever 26, does not attach directly to the end of bar 24, but to an interposed sleeve 28, within which this 20 bar may rotate, the sleeve being longitudinally confined on bar 24, between two collars 29 rigidly affixed thereto. For purpose of such rotation, a chain-wheel 31, is mounted upon bar 24, to which it is operatively held 25 by means of a usual spline which permits bar 24, to shift longitudinally when manipulated by lever 26, without loosening its operative connection with the chain-wheel. This latter is prevented from moving with bar 24, by 30 means of a forked bracket 32, which engages an annular groove in the hub of this chain-wheel and is attached to the rear wall of box D. Wheel 31 is rotated by another wheel 33, of equal size, both being connected 35 by a chain 30, so that to whatever extent the lower wheel is rotated, the upper wheel will follow likewise. It will now be seen that rotation of bar 24, may be readily controlled for the purpose of bringing any particular 40 one of cams 23 in operative position under its lifting-lever, if means are provided to conveniently gage such rotation. This is done by means substantially shown in our Patent No. 645,575, a graduated dial 34, being used, 45 which is set by means of a handle 35. This dial has as many graduations as there are doors, one for each cam individual to each door. In addition it has a graduation-mark designated "all", and which corresponds to 50 the other cams used for simultaneous action upon all lifting levers and which cams are all alined and in the same position, with reference to bar 24. It is clear now, dial 34, being operatively connected to the lower chain-wheel 33, that this latter will follow the dial when set for any particular door, and its rotation is transmitted to an equal extent to the upper wheel 31, and by it to bar 24.

This arrangement whereby any particular 55 door may be unlocked or all of them simultaneously, requires of course a corresponding arrangement of the means for sliding the unlocked doors open. In other words the adjusting of the door-unlocking means for any 60 certain door must also be accompanied by an

equivalent adjustment of the door-opening means, so that an opening-arm Q, on door bar P, is in proper position at the right time when a particular door has been unlocked. This is accomplished as follows: Door-bar P, 70 in addition to its longitudinal movement before described, is also arranged to rotate to an equal extent with locking-bar 24, such being arranged by a set of gear-wheels 36, one mounted on each bar, see Fig. 1, also Fig. 75 11. These wheels are supported in a bracket 37, attached within casing L, to the cell-front and in which bracket, these gear-wheels are fixedly held against longitudinal movement, operative connection for rotation being maintained with each bar by grooves and keys the former being in the shafts. The gear-wheels are of equal size, to that the extent of rotation for each bar is the same. We show 80 an idler between them which is however of no significance and merely done to keep the size of the gear-wheels down to suit casing L. Since worm R, cannot and should not participate in this rotation, a coupling 38, is provided between it and door-bar P, whereby 85 both are endwise connected for joint longitudinal movement, while bar P, is at the same time free to rotate independently of the worm, see Fig. 12. Arms Q, are distributed 90 radially around bar P, in a manner corresponding to cams 23, so that each projects 95 radially in a direction different from all others, the arrangement being such that when a cam is set to raise the latch-bar of any particular door, to unlock the same, the arm 100 to be used to slide such door open arrives also at the same time, by reason of the simultaneous rotation of bars 24, and P, in proper position between its corresponding lugs q—q, on 105 the door, and is ready for action. There is 105 also a second set of arms Q, all alined and projecting all in the same direction from bar P, to simultaneously move all doors, there being such an arm on each of the hubs which carries the other arm, and which set corresponds to the similarly arranged set of cams on bar 24, whereby all doors are simultaneously unlocked. 110

The simultaneous rotary adjustment of bars 24, and P, is best illustrated in Fig. 1, 115 where cam 23, on bar 24, has been set for unlocking the door of the first cell A, while arm Q, on bar P, has also been set for sliding this door open as soon as unlocked. In Fig. 4, 120 bar 24, has been shifted to the right whereby cam 23, acts upon the lifting-lever above it so that the same door becomes now unlocked. After this bar P, is also moved to the right whereby arm Q, slides the door open (the parts being shown in this act.) Cam 23 remains in position under its lifting lever above it, until the door catches 15, carried by the door have become clear of the latch-bar, as shown in Fig. 4, note also position of slots 21 and 17. As will be observed these manipu- 125 130

lations have not affected any of the means used for manipulating the door of any other cell (note adjoining cell, in same figure.) Preceding the adjustment for opening any 5 other door, bar 24 is shifted back again to a neutral or inoperative position with reference to the lifting levers 22, as shown in Fig. 1, in which position it may be freely rotated without interference by said lifting levers 10 and set to the proper adjustment for unlocking another door, after which the procedure is as before.

For sliding any particular door into closed position, its corresponding closing 15 arm Q, is adjusted by manipulation of handle 35. This of course cannot be done without rotating bar 24, at the same time. By leaving this bar however in its neutral position as above described and as shown in Fig. 20 1, unlocking cam 23 thereon, will not affect any of the lifting levers above it, and the latch bars remain in their lower position and ready to receive and hold catches 15, of any 25 door, which becomes locked as soon as moved into its closed position.

A door may be slid open entirely, or remain partly open in any intermediate position in which it is left, by breaking the engagement between it and its particular 30 moving arm Q. This is done by manipulation of handle 35, whereby bar P, is caused to rotate so as to swing such arm out from between its complementary lugs q—q. A door may be picked up again from such an 35 intermediate position by moving bar P, lengthwise with the particular arm Q previously readjusted by rotation of said bar to proper position, that is vertically below it. When bar P is moved lengthwise now and 40 arm Q approaches lugs q q, it depresses the first one encountered, they being yieldingly seated upon springs, and after having passed over this lug, they being inclined at their upper ends to facilitate this, and having 45 arrived again in the space between these lugs, (the depressed lug returning immediately to its normal position), said arm becomes positively engaged again between the lugs and operative connection of the door to 50 its manipulating means is reestablished.

In addition to the two positions of the unlocking cams 23, obtained by two longitudinal adjustments of bar 24 as already explained, the neutral one being shown in Fig. 55 1, and the operative one for unlocking in Fig. 4, there is a third adjustment of this bar as shown in Fig. 5, which we call the deadlocking position, and the effect of which is that all latch-bars are positively held down 60 by their lifting levers. For such purpose bar 24, by means of lever 26, is moved to the left, sufficiently so to bring circular cams 39, under the free ends of all the lifting-levers, whereby the movement of these latter, necessary to permit raising of the latch-bars, is

prevented. Lever 26, carries a usual locking pawl, whereby in conjunction with a notched arm 41, it may be locked, to hold for the time being, bar 24, in either of its adjusted positions.

A condensed resumé of the various manipulations explained in connection with the figures of the drawings is now in place. The operating parts for manipulating the means for unlocking and locking the doors and for 70 moving them laterally are contained in a box D, provided with a lockable door to control access to them. Handle 35, is used to rotate bar 24, while in neutral position as shown in Fig. 1, to adjust the cams 23 thereon preparatory to the unlocking of either any one particular door, or of all of them. By shifting thereafter by means of lever 26, the bar so adjusted length-wise to the right as shown in Fig. 4, any particular door or all of 80 them may now be unlocked, according to the preceding adjustment. In Fig. 1, the door of the second cell B, is open, in Fig. 4, it is closed. Cam 23, in Fig. 1, is set for unlocking the door of the first cell A, while in Fig. 4, 85 said cam by manipulation of bar 24, by means of lever 26, has been shifted to the right, to unlock this door. The rotary adjustment of bar 24, has also caused rotation of bar P, and adjusted the particular door-moving arm Q, thereon for engagement with 90 unlocked door to slide it open. In Fig. 4, this opening movement is shown, it being done by moving rod P, to the right. This operation is performed by manipulating 95 crank-handle w, so as to rotate sleeve P) with stationary nut r, thereby pushing out worm R, coupled to end of bar P. It will be noted that neither of these manipulations have affected the door of the second cell B, 100 either in its open position shown in Fig. 1, or in its closed one shown in Fig. 4. The mere closing of a door causes it to become also automatically locked by engagement of its catches 15 with latch-bars 18, cams 23, to 105 be in neutral position at the time. Note condition of parts with reference to door of second cell in Fig. 1, also see Fig. 13. By shifting bar 24, by means of lever 26, to its extreme position to the left as shown in Fig. 110 5, circular cams 39, engage all the lifting-levers in a manner to hold them immovable, so that the automatically locked doors become now also positively locked or deadlocked. By returning lever 26, to its intermediate position, thereby shifting cams 23, to their neutral or inoperative position as 115 shown in Fig. 1, and by manipulating handle 35, to rotate arms Q, into an intermediate position in which they will not engage any 120 door, all these doors become disconnected from the general operating parts controlled from box D, and each door may be manipulated independently for unlocking by direct manual operation. For such purpose we 125 130

provide locks 42, in the hollow jambs, the bolts of which act against a complementary lug 43, on each latch-bar for the purpose of engaging them directly to raise or lower the same. After a latch-bar has been raised in this manner, the particular door becomes free and may be slid open by hand. In addition to these locks, there are still other locks 44, whereby any door may be dead-locked independently of the general operating means provided for that purpose. The bolt of such a lock when used engages one of catches 15 on the door, by passing into a notch 45, on the lower edge of this catch, thereby holding the same and preventing the particular door from being moved open, even if its latch-bar should have been raised. See Figs. 1 and 13. This lock may be used for instance in a case where the larger number of cells, or perhaps all of them except one, is to be unlocked and in which case this particular cell is dead-locked by it. The doors of all the other cells may thus be unlocked simultaneously, lever 26, being used to advantage, handle 35, having first been set for the "all cells" position. These doors could of course be also unlocked each by itself by use of locks 42 as before described.

A door is held to a straight movement, at its lower edge while sliding, by guide-blocks 46. When in closed position, its rear-edge is firmly held by complementary lips 47, which pass over each other, as best shown in Fig. 14 and interlock. They are preferably made of short pieces of angle-iron, one being secured to the edge of the door-opening, and the other to the rear-upright bar of the door.

The front-wall of casing L, is provided with openings above the cell-doors to permit access to the operating parts for lubricating or other purposes. The doors for these openings are controlled from box D, into which the end of a sliding rod extends which is provided with a handle 48, for manipulation whenever required. (See Fig. 2.) This feature is however not new here.

Crank-handle w, is provided with an opening which may be brought to registering position with a perforated lug 49, within box D. When in such position a pad-lock 50, may be inserted for locking the crank-handle, thereby conferring additional security. See Fig. 6.

It is obvious that special and additional combinations for manipulating the cells may be provided for by arranging the number and position of cams 23 and of arms Q. Thus for instance where there is a row of cells of considerable length, they may be sub-divided for the "all" manipulation in two or three groups, so that instead of manipulating all cells at once, they may be manipulated by groups. This is readily accomplished by arranging the position of the particular cams 23, and arms Q. Or such a manipulation in groups may be added to the "all" manipula-

tion by simply providing an additional wing-cam 23 and an additional arm Q, in each set, analogous to the arrangement indicated in our Patent No. 645,575.

Having described our invention, we claim:

1. In cell-door manipulating means, the combination of a series of aligned, sliding cell-doors, locking means for each which act automatically when a door is closed, two bars supported above these doors parallel to their upper edges, one of which is adapted to be operatively connected to all the locking-means mentioned, the other in like manner to the doors, and means to shift each bar length-wise and whereby, when the first bar is shifted, the locking-means of all doors are acted upon to unlock them, after which when the second bar is shifted, the unlocked doors may be moved in either direction. 85

2. In combination with a series of aligned, sliding cell-doors provided with locking means, a longitudinally movable bar supported above their upper edges, arms rigidly connected to this bar, and complementary projections at the upper edges of the doors adapted to be engaged by the former, and means to adjust this bar length-wise for the purpose of moving the doors from one of their extreme positions into the other one and back again. 95

3. In combination with a series of aligned, sliding cell-doors, a longitudinally movable bar supported above them, means to operatively connect the doors thereto, a worm at one end of this bar, a nut which receives the same and which is supported in a manner to be free to rotate in a longitudinally fixed position, devices to rotate this nut and means to prevent the worm from rotating with the nut. 100

4. In combination with a series of aligned, sliding cell-doors, a longitudinally movable bar supported above them, having also a rotary movement, devices to operatively connect any or all doors to this bar, means to rotate this latter for purpose of such connection and means to slide it longitudinally to move the doors connected thereto. 110

5. In combination with a series of aligned, sliding cell-doors, a longitudinally movable bar supported above them, having also a rotary movement, arms on said bar one for each door, there being also projections on the upper edges of said doors adapted to be engaged by these arms, which arms are mounted in different radial positions so that when one arm engages any particular door, no other door is so engaged, means to rotate this bar for purposes of such engagement, and means to move it with the connected doors longitudinally. 120

6. In combination with a series of aligned, sliding doors provided with locking catches, a vertically movable latch-bar adapted to en- 130

- gage these catches for the purpose of locking the doors, lifting-levers pivotally supported between their ends and each connected with one of its ends to a latch-bar so that, when 5 one of these latter is raised by its connected lifting-lever, the particular door becomes unlocked, a bar supported above the doors in a manner to permit its longitudinal as well as rotary movement, cams mounted thereon, 10 there being one adapted to co-act with the lifting-lever of each latch-bar, each being mounted in different radial position so that, when one cam is adapted to act upon a certain lifting-lever, none of the other cams is in 15 such position, means to rotarily adjust this bar for such action, and means to move the same length-wise after its rotary adjustment, to cause an adjusted cam to act upon its corresponding lifting-lever.
- 20 7. In combination with a series of aligned, sliding doors provided with locking catches, a vertically movable latch-bar adapted to engage these catches for the purpose of locking the doors, lifting-levers pivotally supported 25 between their ends and each connected with one of its ends to a latch-bar so that, when one of these latter is raised by its connected lifting-lever, this particular door becomes unlocked, a bar supported above the doors in 30 a manner to permit its longitudinal as well as rotary movement, cams mounted thereon, there being a set of two adapted to co-act with the lifting-lever of each latch-bar, one cam in each set being so mounted that when 35 it is adapted to act upon its respective lifting-lever, a cam in all other sets is in similar position, so that all lifting-levers may be acted upon simultaneously, the other cams in each set being each mounted in a different 40 radial position, so that when one of them is adjusted to co-act with its particular lifting-lever, none of the others is capable of doing so, means to rotarily adjust the bar for such purpose and means to shift it length-wise to 45 cause the adjusted cams to act upon their respective lifting-levers.
8. In combination with a series of aligned, sliding doors provided with locking-catches, a vertically movable latch-bar for each door 50 adapted to engage these catches for the purpose of locking the doors, lifting-levers pivotally supported between their ends and each connected with one of its ends to a latch-bar so that, when one of these latter is raised by 55 its connected lifting-lever, the particular door becomes unlocked, a bar supported above the doors in a manner to permit its rotary as well as longitudinal adjustment, unlocking and dead-locking cams mounted on 60 this bar, means to rotarily adjust this latter and the unlocking cams thereon to enable the adjusted unlocking cams to act upon the lifting-levers and means to shift this bar length-wise to cause, when moved in one direction, 65 the unlocking cams to pass under the con-
- nected ends of the lifting-lever to raise the latch-bars for unlocking the doors, and when moved in the other direction, to cause the dead-locking cams to pass under the free ends of the lifting-levers, to prevent them 70 from raising the latch-bars.
9. In combination with a series of aligned, sliding cell-doors, locking-means operating automatically for locking them, a bar supported to have a rotary as well as a longitudinal adjustment, cams on this bar adapted to act upon the locking means for releasing the doors, means to rotarily adjust this bar so that only certain cams are capable of such action at a time, means to shift this bar 75 length-wise to cause the adjusted cams to act, another bar also supported so as to have a longitudinal as well as rotary adjustment, projections on this bar adapted to engage the unlocked doors to move them in either direction, operative connection between the two bars whereby, when the first bar is rotarily adjusted to permit unlocking of certain doors, the second bar is also adjusted to engage the doors which are unlocked by the 80 shifting of the first bar, and means to shift the second bar to move the doors unlocked by the first bar.
10. In combination with a series of aligned, sliding cell-doors provided with locking 85 means, a bar supported above them in a manner to have a rotary as well as a longitudinal adjustment, intervening unlocking means adapted to be actuated by this bar to act upon the locking-means, means to rotarily adjust this bar so that the locking-means of certain doors only will be acted upon for 90 unlocking, means to shift this rotarily adjusted bar longitudinally whereby the particular locking-means will be so acted upon, 100 another bar having arms adapted to engage the unlocked doors to move them, gear-wheel connection between it and the bar first mentioned whereby, when the first bar is adjusted to unlock certain doors, the second 105 bar is also adjusted to engage with its arms the unlocked doors, a screw at one end of this second bar, a coupling whereby both are connected for longitudinal movement, a nut fitted to the screw and supported so as to be 110 free to rotate in a longitudinally fixed position, and means to rotate this nut to shift screw and connected bar to move the unlocked door.
11. In means for manipulating, unlocking, 115 opening and closing, sliding cell-doors, the combination with a series of such doors which are aligned, of means which lock automatically when a door assumes its closed position, a door-bar and a locking bar supported parallel above these doors, each in a manner to have a rotary as well as a longitudinal adjustment, intervening unlocking means between the locking-bar and the means 120 which lock the doors automatically, adjust- 125
- 130

ing means whereby the locking bar is caused to operate the unlocking means with respect to certain doors only, means on the door bar whereby the same is operatively connected 5 to the doors, and means whereby the two bars are connected for simultaneous rotary adjustment and which operate so that when the locking bar is adjusted to unlock certain doors, the door bar is automatically connected 10 to the unlocked doors for the purpose of moving them.

12. In combination with a series of aligned, sliding cell-doors, a bar for moving them laterally which is supported so as to be capable 15 of rotary as well as longitudinal movement, arms projecting from this bar in different radial directions one for each door and adapted to engage them, means to rotarily adjust this bar so as to engage a certain door, 20 a worm at one end of this bar, a coupling whereby the two are connected in a manner to permit this bar to rotate independently of the worm, a nut fitted to receive the worm and supported so as to be free to rotate in a 25 longitudinally fixed position, and means to rotate this nut to cause worm and bar to move longitudinally.

13. In combination with a series of aligned, sliding cell-doors, provided with automatically acting locking means, a bar to actuate these means for unlocking these doors, another bar to move them when unlocked, both bars being so supported as to have a rotary as 30 well as a longitudinal adjustment, a door-controlled box at one end of the series of cells into which the ends of these bars extend for 35 their manipulation and means contained in this box for such manipulation.

14. In combination with a series of aligned, 40 sliding cell-doors provided with locking means, a bar to actuate these locking means for unlocking these doors, another bar to move them when unlocked, both bars being supported to have a longitudinal movement 45 for such purpose, they being also capable of a rotary adjustment whereby certain doors only are acted upon by them, an inclosure at one end of the cell-series into which the ends of these bars extend for manipulation, 50 means provided in this inclosure and connected to the end of one of these bars to rotarily adjust the same, means whereby both bars are operatively connected to each other so that rotation of one bar causes also rotation of the

other, and manipulating means in the inclosure whereby each bar may be moved longitudinally.

15. In combination with a series of aligned, 55 sliding cell-doors provided with locking means, two longitudinally movable bars 60 adapted to be operatively connected to these doors, one bar to unlock them, the other one to move them after unlocked, a worm at the end of this latter or door-moving bar, a nut fitted to this worm, a sleeve upon one end of 65 which the nut is rigidly mounted, means which support this sleeve so as to permit it to rotate in a longitudinally fixed position, a lever to shift the unlocking bar lengthwise, and means to rotate the sleeve. 70

16. In combination with a series of cell-doors provided with locking means, a rotarily supported and longitudinally movable bar, a series of wing-shaped unlocking cams radially projecting from the bar, one for each 75 door, a circular, dead-locking cam at the end of each wing-cam, and means to adjust the bar so that either one of the cams only affects the locking means.

17. In combination with a series of sliding 80 cell-doors, a door-moving bar supported to permit longitudinal movement, arms on this bar, one for each cell-door, and spring-actuated lugs inclined at their upper ends carried by the doors and spaced to receive between 85 them, one of the arms mentioned.

18. In combination with a series of cell-doors provided with catches, vertically movable latch-bars provided with slots which these catches are adapted to occupy when a 90 door is closed and in which position they become engaged by the latch-bars, thereby locking a door, means to manipulate the latch-bars from a distance to release the catches engaged thereby, a lock located at 95 each door and a notched projection adapted to engage with the bolt thereof, after which, when so engaged, a door is held in locked position, irrespective of the latches and without interfering with their manipulation. 100

In testimony whereof we hereunto affix our signatures in presence of two witnesses.
